GRAIN DOOR AND METHOD OF FORMING

Michael J. Ford, Hartsdale, N.Y., and Barton H. Ford, Omaha, Nebr., assignors, by mesne assignments, of one-half to International Paper Company, New York, N.Y., a corporation of New York, and one-half to The Stanley Works, New Britain, Conn., a corporation of Connecticut

Filed Dec. 8, 1958, Ser. No. 778,790

5 Claims. (Cl. 160—368)

This invention relates to a grain door and method of forming the same, and, more particularly, to a closure for a railway car doorway to prevent the escape of granular material from the car.

An object of the present invention is to provide a grain door and method of forming the same whereby the door can be fabricated in an inexpensive manner and set up and employed with a minimum of labor and effort. Another object is to provide a method for fabricating a grain door that lends itself to machine operations so that the door can be completely fabricated at low expense while at the same time providing a door which may be installed with important new advantages. A still further object is to provide a grain door which may be completely fabricated and equipped with reinforcing means at the site of manufacture so that a minimum of work is entailed in installation. Yet another object is to provide a novel grain door and method of fabricating the same in which the door at the time of fabrication is equipped with edge-reinforcing means that are effective to protect and maintain the door during storage and handling prior to installation and which serves to effectively bolster the door when installed. Other specific objects and advantages will appear as this specification proceeds.

The invention is shown, in an illustrative embodiment, by the accompanying drawing, in which—

FIG. 1 is a fragmentary perspective view of a railway car interior and having a closure of the invention installed in the doorway thereof;

FIG. 2 is an enlarged cross-sectional view taken along the line 2—2 of FIG. 1;

FIG. 3 is a fragmentary elevational view of the closure in an intermediate stage of fabrication; and

FIG. 4 is a sectional view, taken along the line 4—4 of FIG. 2.

In the illustration given, the letter A designates generally a railway freight car such as is employed in the transport of grain. The car A is equipped with a floor designated by the letter B and with walls C in which a doorway D is provided. The doorway D is defined in part by the vertical side posts 10 seen only in FIGS. 1 and 4. Installed across the doorway D and secured to the inner surfaces of posts 10 is a closure of the invention, designated generally by the numeral 11.

The closure 11 is a generally rectangular panel and includes two laminated panels 12 and 13 which are united in superposed, face-to-face relation.

Each panel 12 and 13, as illustrated, is a corrugated paperboard panel having outer liners and a central corrugated core. As best seen in FIG. 4, the panel 12 is equipped with liners 12a and 12b, the liner 12b being spaced inwardly of the posts 10. The corrugated core of panel 12 is designated by the numeral 12c, and can be best seen in FIG. 2 since the flutes of the corrugations in core 12c extend horizontally. In similar fashion, panel 13 is equipped with liners 13a and 13b, with liner 13b providing the interior surface of the closure 11. Also, panel 13 is equipped with a corrugated core designated by the numeral 13c, which can be best seen in FIG. 4 inasmuch as the flutes of the core extend vertically. Each

2

panel 12 and 13 is equipped with spaced-apart, flat metal straps 14 and 15, respectively. The straps 14 and 15 in each panel 12 and 13 are arranged parallel to an edge of the panel and are positioned interiorly of the panel as between a liner and the corrugated core. As illustrated, the straps 14 are positioned between liner 12a and core 12c, while the straps 15 are positioned between the liner 13a and the core 13c. The straps 14 of panel 12 extend transversely of the direction of the flutes, so that the straps are vertically disposed, as can be readily appreciated from a consideration of FIG. 1. The straps 15 of panel 13 are likewise disposed transversely of the direction of the flutes in the corrugated core 13c, and, also as seen in FIG. 1, extend horizontally. Thus, the straps in the respective panels extend transversely of each other. Also, as seen in the drawing, the straps are spaced inwardly of the side edges of the panel to which they are parallel.

The panel 12 is equipped with a portion 16 adjacent the top edge of the closure 11 that is folded on itself and is positioned interiorly of the inner side of panel 13. The folded portion extends across the doorway D as seen in FIG. 1, and is secured to the posts 10 by means of nails or other securing means 17. The straps 15 are likewise secured at their ends to the posts 10 by means of nails 18. To facilitate this securing, the closure 11 may be equipped with openings extending therethrough in positions suitable for the receipt of nails 18.

As illustrated, the panel 12 is equipped with a second folded portion 19 lying along the interior lower edge of the closure 11. The folded portion 19, like the folded portion 16, is achieved by providing an extension or overlapping portion in the panel 12 relative to the panel 13. The overlapping portion, at an intermediate stage of fabrication, is designated in FIG. 3 by the numeral 16a relating to the top overlapping portion and the numeral 19a relating to the bottom overlapping portion.

In the fabrication of the door, the corrugated panels 12 and 13 may be provided from the same continuous web, designated generally by the numeral 20 in FIG. 3. By severing a portion of the web and disposing it transversely of the web to provide the panel designated 12 in FIG. 3, the closure 11 can be expeditiously formed. The web 20 is interiorly equipped with the straps 14 and 15, which may be two inch wide bands of from 16 to 22 gauge sheet steel. Once the parts are assembled, as seen in FIG. 3, the panel 12 may be united to the web 20 by any suitable means. Adhesively uniting the two parts 12 and 20 provides a strong, integrated closure, and for that reason is preferred. Thereafter, the web 20 may be transversely severed to provide a closure 11 of the desired width. At this time, the overlapping portions 16a and 19a can be folded on themselves to provide the folded portions 16 and 19 seen best in FIGS. 1 and 2.

In the operation of the invention, the completed closure is provided usually equipped with the portion 16a in the condition seen in FIGS. 1 and 2. Optionally, the portion 19a may be left unfolded and when installed provides a floor flap for the grain door. When folded in the form designated 19, the door is then equipped with a pry-board in which the flat metal straps 14 are conveniently located near the outer surface of the pry-board so as to serve as bearing surfaces for a crowbar, or the like, when the closure 11 is to be removed.

The shipment and handling of the closure 11 is facilitated by the presence of the folded portion 16, since this serves as a reinforcement member for the closure 11 to conserve it against deformation. Preferably, at least one of the panels is equipped with a corrugated core, this panel being panel 13, in which the flutes run transversely to the reinforcing portion 16. The tendency in panel 13 is to collapse along lines parallel to the direction of the

flutes, and this is effectively opposed by the reinforcing portion 16.

By providing the corrugations in the panel 12 in the direction shown, folding of the overlapping portions 16a and 19a is readily achieved. However, the advantages of the invention can be achieved when the flutes of the corrugated core 12c run otherwise than shown, since folding is readily accomplished if the corrugated core is slightly crushed along the lines of folding.

When the closure 11 is installed as seen in FIG. 1, the bottom folded portion 19 being secured by nails 21 to the posts 10, the interior straps 14 and 15 cooperate to substantially minimize the deformation of the closure due to the pressure of the granular cargo. Through the use of a minimal number of straps arranged transversely to each other, the deformation is effectively resisted. Heretofore, it was believed necessary to use a large number of straps in order to achieve this resistance. Here, the presence of only two vertically-extending straps 14 effectively reinforces the horizontal straps 15 so that only two of these are required. The vertical straps 14 act as columns secured at both ends by virtue of the fact that the straps 14 are effectively anchored at their ends in the folded portions 16 and 19. In the event the bottom overlapping portion 19a is not folded but employed as a floor flap, a conventional pry-board is installed and serves as the stabilizing means for the lower end of the straps 14.

Thus, we have provided a closure which is, in effect, self-contained and ready for immediate installation at any time after it has left the factory. No longer is it necessary for the mechanics employed for installing doors to rip apart the door to get at the straps, install the side battens and other reinforcing boards—all of this while having to worry about non-uniformly tensioning the door, which might result in a premature failure. Here, the closure is self-supporting and requires securement only at a minimum number of points, so that the problem of non-uniform tension is effectively avoided.

While, in the foregoing specification, we have set forth a specific structure in considerable detail for the purpose of illustrating an embodiment of the invention, it will be understood that such details of structure and procedure may be varied without departing from the spirit of the invention.

We claim:

1. In a temporary closure, a first laminated, generally rectangular, paperboard panel interiorly equipped with a plurality of thin flat, spaced-apart straps all parallel to a pair of edges of said panel, said panel having a corrugated core interposed between liners, a second laminated paperboard corrugated core-equipped panel also strap-equipped and secured in face-to-face relation to said first panel with the straps of the two panels disposed generally transversely relative to each other, with the straps in each panel extending transversely to the direc-

tion of the flutes in the core of its associated panel, said second panel having a dimension in the direction of its straps longer than the dimension of the first panel transverse of its straps to provide an overlapping edge portion 5 in said second panel, said overlapping edge portion being folded on itself to provide a closure reinforcing member adjacent the edge of said first panel.

2. The structure of claim 1 in which the straps in said second panel are adjacent the side of its panel core remote from said first panel.

3. In combination with a car doorway opening having vertically-extending side posts, a closure extending across the doorway and abutting the inner faces of said posts, said closure comprising a pair of laminated panels united 15 together in face-to-face relation, one of said panels being interiorly equipped with horizontally-extending thin flat straps, while the other of said panels is interiorly equipped with vertically-extending flat straps, each of said panels being equipped with a corrugated core having the flutes thereof disposed generally perpendicularly to the straps thereof, the other panel having its upper end portion folded on itself to form a reinforcing member extending horizontally across said doorway, securing means extending through said member into said posts, and means securing 20 said horizontally-extending straps to said posts.

4. The structure of claim 3 in which said other panel has its lower end portion folded on itself to form a second reinforcing member, and securing means extending through said second member into said posts.

5. In combination with a car doorway opening having vertically-extending side posts, a closure extending across the doorway and abutting the inner faces of said posts, said closure comprising a pair of laminated panels united together in face-to-face relation, one of said panels being 30 equipped with a group of horizontally-extending thin flat straps, while the other of said panels is equipped with a group of vertically-extending thin flat straps, said strap groups thereby being oriented perpendicularly to each other and disposed internally of said closure, each of said 35 panels being equipped with a corrugated core having the flutes thereof exposed generally perpendicularly to the straps thereof, the other of said panels having its upper end portion folded on itself to form a reinforcing member extending horizontally across said doorway, securing 40 means extending through said member into said posts, and means securing said horizontally-extending straps to said posts.
